UNITED STATES PATENT OFFICE.

PAUL E. BÜTOW, OF BROOKLYN, NEW YORK.

DIAPHRAGM.

1,334,435.

Specification of Letters Patent. Patented Mar. 23, 1920.

Application filed May 5, 1917. Serial No. 166,531.

To all whom it may concern:

Be it known that I, PAUL E. Bütow, a citizen of the United States, and resident of the city of New York, borough of Brooklyn, county of Kings, and State of New York, have invented a new and Improved Diaphragm, of which the following is a full, clear, and exact description.

This invention relates to sound recording and reproducing machines and has particular reference to the construction of the sound boxes or reproducers of such machines, and by the term sound boxes, as used herein, I mean to cover any analogous device for use on any kind of sound recording or reproducing mechanism.

Among the objects of the invention is to specifically improve the construction of the diaphragm whereby it is expedient to record and reproduce the tones of the human voice or other familiar sounds in the most faithful manner.

Another object of the invention is to produce a diaphragm for sound boxes in a novel and peculiar manner whereby, in connection with musical productions, the tones produced are of the fullest, clearest and sweetest quality, as well as being practically exact reproductions of the original tones.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings, in which like reference characters designate the same parts in the several views, and in which

Figure 1 is a side elevation of my improved device showing a stylus and stylus bar in connection therewith; and

Fig. 2 is a vertical transverse section of the same on the line 2—2.

Referring now more particularly to the drawings I show a sound box comprising a shell 10 of any suitable rigid material, the main portion of which is bell shaped or curved preferably in an ogee curve all the way from the short cylindrical rim 11 into the coupling neck 12. As a sound box is ordinarily made and used it is of a flat nature with a more or less abrupt shoulder or offset between the flange or mouth portion where the diaphragm is connected to the re-

stricted shank or neck portion, the result being that the tones originating in the diaphragm are seriously disturbed or broken in their movement from the diaphragm to the neck and tone arm to which the sound box is connected. By reference to Fig. 2 therefore it will be appreciated that by providing the gracefully curved interior of the shell of the sound box without sharp angles or shoulders the tones from the diaphragm will pass without material damage or obstruction into and through the tone arm for delivery from the machine.

As a result of long experiments and experience in this art I have discovered that sound box diaphragms may advantageously be made of metal, if they can be formed thin enough and of uniform thickness. I have discovered furthermore that it is practically impossible for a diaphragm to be made of metal thin enough for best results so as to maintain its perfect integrity, by rolling or stamping.

According to my improvement therefore I provide a diaphragm 13 of thin spun metal of uniform thickness which, by way of example should be about .002 of an inch thick or less, and the metal I prefer to use for this purpose which I have found to be preëminently successful is a soft quality of aluminum. As shown best in Fig. 2 the sheet or disk of metal is provided with a plurality of concentric convolutions or corrugations 14, 15 and 16 at its central portion while the outer rim portion is left flat as indicated at 17. The radius of the flat portion is indicated as approximately $\frac{1}{2}$ that of the corrugated portion. It will be noted also that the crests of the convolutions project in opposite directions or on opposite sides of the central plane of the flat portion 17. The periphery of the diaphragm is preferably gripped between two soft gaskets 18 and held in place by a spanner ring 19 within the short cylindrical rim portion 11 of the box.

The diaphragm as thus far described has been found in practice to be exceedingly satisfactory but because of its extreme thinness has been found somewhat delicate to manipulate. I therefore provide some suitable reinforcement means for the central portion to which the stylus bar 20 is connected in the usual manner. The reinforcement means that I prefer to employ comprises a small thin disk of celluloid 21 or 22 secured on

either or both of the faces of the central portion of the diaphragm, the securing being accomplished by any suitable flexible cement such as gum arabic or its equivalent. These 5 small disks of celluloid are both preferably of a thickness substantially equal to the thickness of the spun aluminum diaphragm or not to exceed approximately .002 of an inch. I wish to observe also at this time that 10 the peripheries of the reinforcement disks, when two are used, substantially coincide with each other or reach radially to about the crest of the second convolution 15 leaving one of the convolutions and the flat portion 15 of the diaphragm of single minimum thickness.

The formation of a diaphragm of spun metal instead of rolling, stamping or otherwise forming them, possesses numerous advantages, among which may be noted the following:

As above premised it is essential for the best quality reproduction of musical tones or for the most faithful reproduction of the 25 human voice or other familiar sounds that the metal diaphragm be extremely thin. Furthermore the texture of the metal, while being exceedingly thin, ought to be homogeneous and unbroken throughout. In other

words there should be no parts or spots that 30 are shattered, ragged or broken. From my experience in the working of thin metals I am convinced that there is no practical way of forming a resonant metal thin enough for the practical purposes of my improved 35 diaphragm in any other manner than by spinning, whereby all of the molecules of the sheet of metal are caused to be arranged in a uniform manner adapting them to the creation or formation of an extremely thin 40 and uniform sheet.

As indicated above the reinforcement disks 21 and 22 may be made of thin celluloid, but it is obvious that other materials than celluloid may be used for this purpose. 45 For instance I may form them of spun aluminum similarly to the formation of the main portion of the diaphragm. To secure the best results I have discovered that the total thickness of the reinforced portion 50 should not exceed approximately .004 of an inch, or twice the thickness of the main diaphragm.

I claim:

A diaphragm for sound boxes comprising 55 a thin sheet of spun aluminum.

PAUL E. BÜTOW.
